N° 996.

Design for a Cooking Stove.

by George W. Pittock, George G. Richmond and Charles Phelps, of Troy, N.Y.
Assignors to Themselves and Jacob Brown, of the same place.

Patented April 6. 1858.

Dec. 996

J. W. Pittock, G. G. Richmond, & C. Phelps, of Troy, N.Y.

Assignors to

J. W. Pittock, G. G. Richmond, C. Phelps, J. Con. of Troy aforesaid.

Letters Patent No. 996, dated Apr. 6th 1858.

The schedule referred to in these Letters Patent and making part of the same.

To all whom it may concern:

Be it known that we, George W. Pittock, George G. Richmond, and Charles Phelps, each of the city of Troy, in the County of Rensselaer and state of New York, have jointly invented or produced a new and original design for plates of a Cooking Stove, called the "Olympia," and we do hereby declare that the following is a full and exact description of the same, reference being had to the annexed photographic drawing, making a part of this specification.

In our ornamental design for plates or castings of a Cooking stove, each foot has the shell, a, upon the scale-work surface b. Each side-plate has a row of angular projections, c, along the bottom and ends; - the fine wave-like moldings, d, along its upper projecting part; - and the fixed panel E, and two panel-doors F, G, each of which has the outer plain hollow molding h, - a middle row of the oval projections, i, the inner wave-like molding j, & the central compound ornament, K. - The front plate has an outer row of the angular projections, c, and the inner double wave-like molding, l, along each end; and the row, m, of alternate shells and letters above its two panel doors, N. O, each of which latter has the outer plain hollow molding h, - a middle row of the projections, i, the inner wave-like molding, j, and the central compound ornament K, the same as the doors and panels of the side plates.

What we claim as our invention or production and desire to secure by Letters Patent is the combination and arrangement of figures, forms & moldings, herein specified and represented in the annexed photographic drawing, forming the ornamental design of the plates or castings of a Cooking Stove.
